UNITED STATES PATENT OFFICE.

HEBER C. PETERS, OF NEW YORK, N. Y., ASSIGNOR TO BURROUGHS ADDING MACHINE COMPANY, OF DETROIT, MICHIGAN, A CORPORATION OF MICHIGAN.

ADDING-MACHINE.

1,310,963.

Specification of Letters Patent. Patented July 22, 1919.

Application filed April 14, 1905. Serial No. 255,637.

To all whom it may concern:

Be it known that I, HEBER C. PETERS, a citizen of the United States, residing at the city, county, and State of New York, have 5 invented certain new and useful Improvements in Adding-Machines, of which the following is a specification.

My invention relates to what are commonly known as adding machines, more 10 especially to that type thereof capable of printing, listing and adding or accumulating individual items and of printing the total thereof, such as a Burroughs adding machine, made substantially in accordance with Letters Patent of the United States Nos. 504,963 and 505,078, issued on September 12, 1893, on the inventions of William S. Burroughs, said machine being further described in Patent No. 823,474, issued June 12, 1906, on 15 the application of Alvan Macauley. The object of my invention is to provide an adding machine of this general type or character with means for separately adding or accumulating the items of a series or plurality of different columns and for keeping such accumulations or footings independently of the grand total or accumulation of all the items in the different columns, in such manner that, at the will of the operator, the machine may be caused to print the footings or totals of the separate columns as 20 well as the grand total of all of the footings if desired. Moreover, according to the present embodiment of my machine and by preference, I also provide for cross addition of the items in the different columns, so that when the usual accumulating mechanism of a Burroughs machine, for instance, is retained, the cross totals may be printed 25 and separately accumulated into an independent grand total which, if the work is correct, should equal the grand total of the separate footings of the columns, in the present instance, I have shown and I will hereinafter describe my invention as embodied 30 in a machine of the Burroughs type, but it will be understood that my invention is not limited in its application or scope to such machine, but that the same may be used in connection with machines of the same general character and used for the same purposes.

In the drawings, Figure 1 is a side elevation of a Burroughs machine with my im-

provements embodied therein, the view being 55 of the left-hand side of the machine; Fig. 2 a plan view of the rearward portion of such machine; Fig. 3 a side elevation of certain parts of a Burroughs machine, as well as certain details or parts of my improvements, the parts being shown full size and the view being the left-hand side thereof; Fig. 4 a view similar to Fig. 3 but of the right-hand side of the parts; Fig. 5 a detail view of some of the parts constituting my 60 improvements, this view being on a somewhat enlarged scale; Figs. 6 and 7 details of certain parts concerned with the carrying mechanism; Fig. 8 an elevation of some of the parts or attachments constituting my 65 improvements; and Fig. 9 a perspective of the means for operating the parts illustrated in Fig. 8.

Inasmuch as the Burroughs machine is well known as to construction and mode of 70 operation and is also described as to its general principles in the Burroughs patents aforesaid, only those parts of the mechanism will be explained or referred to which are more or less directly concerned with the 75 construction and operation of my improvements which, in the present instance, constitute attachments to the machine, whereby the additional results, hereinbefore referred to, may be attained.

As is well known, the Burroughs machine is provided with a keyboard having a series of keys 291 arranged in rows representing the different denominations, increasing from right to left and the keys of each 80 row representing the digits 1 to 9. These keys are arranged to control or operate a series of stop wires or rods 270 which determine the degree of movement or descent of a series of sectors, or racks 610 corresponding in number to the rows of keys, it 85 being understood that in the operation of the machine a rack corresponding to a row of keys in which one of the keys has been operated, is permitted to descend a distance 90 corresponding in value to the particular key operated or depressed. Furthermore, on a Burroughs machine these racks are normally locked in their raised position and remain in such condition until their retainers or 95 locks 415 are removed from locking engagement therewith, it being understood that 100 each rack is provided with a retainer 415

which is operated by the sliding bar 214 corresponding in number to the rows of keys and moved rearwardly whenever a key in that row is depressed.

5 The racks 610 are carried at the forward end of a series of main levers or sector bars 611, corresponding in number with the rows of keys and hung intermediate their length upon a main transverse shaft 600. The 10 rearward ends of these levers carry the usual movable type plates 618, any one of which is arranged to be presented to the platen 1599 according to the degree of movement of the levers, as permitted by the racks and 15 as determined by the particular key or keys operated.

The racks 610 coöperate with a series of adding wheels or dials 912 which are arranged in a frame having the side plates 910 20 rocking on shaft 900, whereby such wheels may be rocked into and out of coöperative relation with their racks for the purpose of receiving the value or amount from such racks and also for the purpose of causing 25 the total on the adding wheels to be transferred to the racks in the operation of taking a total, Fig. 1. The construction and mode of operation of the accumulating mechanism being so well known, it is unnecessary to describe the same in detail, and it will, therefore, suffice to state that upon the first movement or rocking of the main operating shaft, or of an operating handle, if the handle is employed, the adding wheel 30 frame 910 is swung forwardly so as to carry the adding wheel pinions 916 out of mesh with their racks, such rocking being brought about through the medium of the rocking lever 913 and the pitman 914. The racks 35 corresponding to the rows in which the keys have been depressed will descend distances corresponding in value to such keys, in which operation the rearward or type bearing ends of the levers belonging to the operating 40 racks will be elevated or rocked upwardly corresponding distances so as to present to the platen the figures of digits corresponding to the operated keys. After the amount has been printed upon the paper on 45 the platen, the accumulating mechanism is restored to coöperative relationship with the racks 610, whereupon in the upward or restoring movement of the racks 610, the values are transferred to the adding wheels 50 corresponding to the particular racks which have been operated.

The mechanism just described is that which is common and well known in a Burroughs machine and comprises those parts 55 in connection with which the parts constituting my invention or improvements operate. In general terms my improvements comprise a series or plurality of accumulators which are operated or controlled by the 60 series of main levers or bars 611, with the

result that separate or independent totals may be taken of the items comprised in the different columns and the totals may be separately transferred to the machine and printed, the construction and arrangement 70 being such that this result is attainable whether the items are printed consecutively in vertical columns or crosswise of the sheet of paper in the different columns. Furthermore, under the present embodiment of my 75 invention the Burroughs machine proper keeps a grand total of all of the items, with the result that the work may be proved by subsequently accumulating the totals of the accumulators which represent the footings 80 of the different columns. The total of such footings should of course equal the grand total shown by the regular adding wheels 912 of the machine.

Referring to the present embodiment of 85 my invention, as illustrated in the drawings and as shown incorporated with a Burroughs machine, I employ a series of racks 1 secondary to and independent of the regular racks 610 and arranged parallel to each other, such secondary racks being operatively connected in the present instance, with the rearward or type bearing ends of the main levers or bars 611. These racks correspond in number to the number of the 90 levers and as illustrated in the drawings, particularly in Figs. 1, 3, 4 and 5, each rack has a pin and slot engagement with its lever 611, to which end each lever has an upwardly projecting slotted plate 2 arranged 100 to receive a pin 3 projecting laterally from each rack. The racks are arranged to move upwardly whenever their corresponding levers are operated or rocked on the shaft 600 as an axis and in order to guide these racks 105 they are provided with curved slots 1* through which the fixed transverse shaft 500 passes, each slot corresponding of course to the arc of movement of its rack. The rearward edge of these racks is provided with 110 a series of teeth arranged to coöperate with the series of pinions arranged in different groups, which pinions or groups of pinions I will hereinafter term accumulators, inasmuch as they serve to accumulate and not 115 to indicate. The racks are normally held separated from their levers a distance of one tooth against the tension of their springs 4 by means hereinafter explained.

The accumulators are mounted on a frame 120 movable transversely of the machine, and by preference, and as shown in the drawings, such accumulators are arranged on and movable with the paper carriage itself which is a laterally shiftable one of the general construction illustrated in Pike Patent No. 595,864, issued December 21, 1897, and I will 125 now proceed to describe these accumulators according to their present illustrated construction and arrangement, without intention 130

tion of limitation thereto. It will first be understood that any number of accumulators may be employed and the number of pinions comprised in each group may be varied, the number of pinions in each accumulator corresponding to the number of rows of keys of the particular machine in which my invention may be embodied. In the present instance, as illustrated clearly in Fig. 2, I employ a series of seven accumulators so as to accommodate and take the independent footings of seven different columns of figures on a single sheet of paper, or of six different columns in the event that the last accumulator on the right is employed to accumulate the cross totals of the independent items, as hereinafter explained, but it will be understood that the number of these accumulators may be varied as desired and also that all of the accumulators need not be employed if present.

In the present instance each accumulator consists of a series of nine similar pinions 5 which are mounted in a rocking frame or bail comprising a transverse shaft 6 and parallel side arms 7 which are pivoted at their lower ends upon a rod or shaft 8, Figs. 3 and 4. This rod or shaft extends between the two side plates 9 which are secured to or form a part of the end frame or brackets of the platen frame extended for the purpose. It will be understood that all of the pinions of the different sets or groups of accumulators are mounted on the shaft 6, with the result that the pinions may be rocked rearwardly or forwardly in the automatic manner hereinafter described. For the purpose of limiting this forward and backward movement of the rocking frame or bail which carries the accumulators, the side arm 7 contacts with the pins or studs 10 and 11, as illustrated in Figs. 2, 3 and 4. Each accumulator is provided with means for locking the pinions and, in the present instance, such means consists of a series of rocking bails or frames 12 pivoted at their lower ends upon a transverse rod 13, whose ends are secured in the side plates 9. The upper ends of these frames are provided with corresponding teeth 14 corresponding in number to the number of pinions in its accumulator, there being nine of such teeth in the present instance. Each locking device is normally held forwardly with yielding pressure, as by means of the spring 15, and the arrangement is such that the pinions of the different accumulators are always locked when swung rearwardly, and all of them are locked when swung forwardly with the exception of the particular accumulator which is presented to the series of racks 1. For the purpose of thus interfering with the action of the locking device of this particular accumulator and thereby permit the racks 1 to transfer their values thereto, in the manner hereinafter explained, I provide suitable means comprising, in the present instance, an arm 16 secured upon the shaft 500 and projecting rearwardly with its free end terminating in a foot arranged in the path of movement of one of the side bars of each of the rocking frames 12 as they are presented in operative relationship with the machine. It will be understood that this arm 16 holds the locking device of that accumulator only which is in operative position, as clearly indicated in Figs. 2, 3 and 4. Suitable transfer or carrying mechanism, hereinafter described, is provided, to cause each accumulator pinion, when it completes a revolution, to turn the next higher pinion in the series one step.

When an item or amount has been set up on the keyboard of the machine and the machine operated the levers or bars 611 are rocked upwardly as to the rearward ends in the well known manner and the racks 1 corresponding to the particular levers which have been operated are likewise elevated or rocked upwardly after the accumulators have been rocked rearwardly in an automatic manner, as hereinafter explained. After the item or amount has been printed upon the paper on the platen 1599 the accumulators are permitted to be restored to normal position, that is to be rocked forwardly, with the result that the particular accumulator which is in proper position to coöperate with the racks 1 will be put into mesh with their rack teeth and those pinions corresponding to the operated racks 1, will, upon the restoration of the parts and the consequent downward movement of the racks, be turned or rotated distances corresponding in value to the values of the keys operated. In other words, the item or amount set up on the keyboard is accumulated on the particular accumulator in action at the time, in the present instance, Fig. 2, this accumulator being the fourth or middle one of the series of accumulators.

For the purpose of automatically rocking the accumulators forward and backward, so as to engage their pinions with and disengage them from the racks which actuate them, I provide in the present instance the means which may now be described, consisting of a lever 29 fulcrumed near its lower end upon the shaft 501, Figs. 1, 2 and 8, with means for rocking said lever to cause its upper end to swing the upper end of the accumulator frame rearward at the proper time, to disengage the accumulator pinions from the racks, and to permit it to swing forward again at the proper time to re-engage said pinions with the racks. The shaft 6 is provided, at the ends of the accumulator sections, with collars 30, against which the upper end of the lever 29 bears.

As shown in Fig. 2 the right hand upper

end of the lever 29 consists of a straight vertical arm, at the lower end of which the lever is bent outwardly or to the left, at right angles, and thence extends downwardly to its pivotal support upon the shaft 501. The right hand vertical arm of the lever is rigidly connected by a cross rod 31 with a lever 32 fulcrumed on the shaft 501 at the left side of the machine, and projecting below said shaft, as shown in Figs. 1 and 8. The levers 29 and 32 fulcrumed on the shaft 501, and the cross rod 31 rigidly connecting them, thus form a rocking frame mounted upon said shaft. This rocking frame is operated by means of a pitman 33 somewhat similar to the pitman 914 which operates the rocking frame 910 of the regular accumulating section of the machine in the usual manner. The forward end of the pitman 33 has a sliding support near the front of the machine upon the cross rod 400, while its rear end is divided into two vertically projecting arms, whose extremities 33^a and 33^b are formed into hooks to co-operate with studs or other suitable projections upon the sides of the lever 32 of the rocking frame before described. A spring 41 connected to the pitman near its forward end normally holds its rear end elevated, with its lower hooked arm 33^a in engagement with the stud 32^a upon the lever 32 of the rocking frame, and with its upper hooked arm 33^b disengaged from the stud 32^b upon said lever.

The pitman 33 is reciprocated backwardly and forwardly, to operate the rocking frame carrying the lever 29, by means of a short pivoted arm or lever 34 which is mounted upon the upper rear end of a supporting bracket 35 secured to the side frame of the machine, Figs. 1 and 9. This lever 34 carries at its upper end a laterally projecting stud or pin 36, which co-operates with a recess formed in the pitman 33 and comprising a lower portion 33^c and an upper portion 33^d, said portions being in the present instance, offset in relation to each other, as shown. A spring 37, connected at its lower end to the pin 36 and at its upper end to a fixed point, yieldingly holds the lever 34 in and returns it to its normal neutral position shown in Figs. 1, 8 and 9.

For the purpose of rocking the lever 34 and thereby reciprocating the pitman 33, there is secured upon the rock shaft 800 of the machine a cam plate 38 into whose path of movement the lower end of the lever 34 projects. When the operating handle of the machine is pulled forward and the shaft 800 thereby rocked rearward (in the usual manner) the cam plate 38 will swing the lower end of the lever 34 rearward and throw its upper end forward, thereby forcing the pitman 33 in the latter direction. During the further rearward movement of

the plate 38 its curved upper edge will travel beneath the lower end of the lever 34 and hold the parts in their moved position until the upper edge of the plate passes rearward of and clears the lower end of the lever, 70 whereupon the spring 37 will restore the latter to its normal vertical position, with its lower end at such time projecting into the path of the return forward movement of the plate 38. This will permit the pitman and connected parts to return to their normal position shown in Fig. 1.

Inasmuch as the hooked lower end of the depending arm of the pitman 33 is normally engaged with the stud 32^a on the lever 32 of the rocking frame, it follows that when the pitman 33 is forced forward as described, at the beginning of an operation of the machine, the lower end of the lever 32 and the rocking frame will be drawn 85 forward and the upper end of the lever 29 be swung rearward, to disengage the accumulator pinions 5 from the racks 1 and prevent the pinions being turned by the racks at the upward movement of the latter; 90 and when the operating handle has reached its limit of forward movement, and the cam plate 38 has passed rearward of and cleared the lower end of the lever 34, the return of the pitman 33 and connected parts to their 95 normal position, as described, will cause the upper end of the lever 29 to be swung forward again and the accumulator pinions permitted to reengage the racks, so as to be turned by the latter during their return 100 downward movement.

In the manner and by the means described, therefore, the accumulator pinions 5 are disengaged from the racks 1 at the beginning of each operation of the machine and reengaged with them at the proper point during such operation, very much as the pinions 916 of the regular adding wheels of the machine are disengaged from the racks 610 at the beginning of each operation and reengaged there-with prior to the return upward movement of said racks; and, as will be understood, at such operation of the machine the amount of any items set up on the keyboard of the machine will be added upon the regular 105 adding wheels 912 of the machine and be also added or accumulated upon the pinions 5 of the particular accumulator which is at that time in register or co-operative relation with the racks 1.

By operating the machine in the ordinary way, therefore, a series of items may be listed in a vertical column upon a sheet of paper and accumulated upon the pinions of the corresponding accumulator. The paper 110 carriage may then be shifted to bring another vertical column on the paper to the printing point and the corresponding accumulator into register with the operating racks 1, and a second vertical column of 115

- items be printed upon the paper and accumulated upon the second accumulator; and so on. In this manner, if the paper carriage be initially set in its extreme right hand 5 position, with the left hand accumulator which it carries in register with the operating racks, seven vertical columns of items may be printed upon the sheet of paper, and the total of each column be accumulated 10 upon the corresponding accumulator pinions; while a grand total of all of the items in all of the columns will have been accumulated upon the regular adding wheels 912 of the machine.
- 15 For the purpose of printing at the foot of each vertical column of items the total of the items contained in such column, the following provision is made: A key stem 39, provided with a key or finger button 40 at 20 its upper end, is pivoted at its lower end to the pitman 33 at a point a short distance in rear of the front end of the latter. By means of this key the rear end of the pitman may be depressed to disengage its lower 25 hooked arm 33^a from the stud 32^a on the lever 33 of the rocking frame and to engage its upper hooked arm 33^b with the stud 32^b on said lever. The result of this disengagement of the lower arm of the pitman from 30 and the engagement of its upper arm with the lever 32 of the rocking frame will be that when the pitman is forced forward, at the beginning of the operation of the machine, the upper end of the lever 29 will be 35 swung idly forward and the pinions 5 be left in mesh with the racks 1, during the upward movement of the latter. The pinions 5 will therefore be turned backward until arrested in zero position, which will cause 40 the type representing the amount previously accumulated upon such pinions to be brought to the printing line, for the printing of the total. After such total has been printed the pinions 5 will be swung rearward, out of engagement with the racks, before the latter begin their return downward movement, so as to leave the pinions in zero position and consequently to "clear" such accumulator. 45 This is due to the fact that at the return 50 movement of the operating handle or main rock shaft, and consequent forward movement of the cam plate 38 which operates the pitman-actuating lever 34, the upper end of said lever will be swung rearward beyond its 55 normal vertical position, and will force the pitman rearward beyond its normal position, and as the upper hooked arm of the pitman is at such time in engagement with the stud 32^b on the lever 32 of the rocking frame 60 which carries the lever 29 the upper end of the latter will be swung rearward beyond its normal position and disengage the pinions from the racks. They will be held disengaged therefrom until, at the end of the 65 operation of the machine, the upper end of the cam plate 38 passes forward of and clears the lower end of the lever 34 and the latter is permitted to resume its normal position under the influence of its spring 37.
- When the key 40 and rear end of the pitman 33 are depressed, for the printing of a total in the manner described, the upper portion 33^d of the notch or recess in the pitman is brought into co-operation with the pin 36 on the lever 34.
- Provision is made whereby the depression of the key 40 releases all of the racks 610 and levers 611 of the machine (as does the depression of the regular total-key of the machine) such provision consisting in the present instance of a swinging bail 43 composed of a pair of pivoted side arms having their upper ends connected by a cross bar or strip 42 lying immediately in rear of the projecting upper ends of the latches or detents 415 80 which normally hold the racks 610 in their upper position; and an arm or link 45 pivoted to said bail at its front end and at its rear end resting upon a stud upon the framework and provided with a pin 46 normally 85 engaging a recess or curved notch 39^a in the forward edge of the key stem 39. When the key 40 is depressed the pin 46 is forced out of said notch and the arm 45 thereby forced forward, swinging the upper end of the bail 43 forward and disengaging all of the detents 415 from their corresponding racks 610.
- By depressing the key or button 40, therefore, and pulling the operating handle of 100 the machine forward and then releasing it, the total amount of any items accumulated upon any one of the accumulators may be printed at the foot of the corresponding column of items, and the accumulator pinions 105 be reset to zero. This printing of the total of each vertical column of items at the foot of the column may be done either at the end of the operation of listing each column of items, or it may be done after all of the 110 columns have been listed. If no totals are printed at the foots of the several columns until the last column of items has been listed, then the grand total of all of the items in all of the columns will be exhibited upon the 115 regular adding wheels 912 of the machine, and this total may be printed upon the sheet of paper and the adding wheels be cleared, after which the totals of the respective columns may be printed at the foots of the several 120 columns by adjusting the paper carriage transversely of the machine to bring the several sets of accumulator pinions successively into register with the actuating racks and operating the machine in the manner 125 heretofore described. If no precaution be taken to prevent it, the printing of these totals of the respective columns will cause such totals to be accumulated upon the regular adding wheels 912 of the machine, so 130

that when the totals of all of the columns have been printed at the foots of the columns the regular adding wheels 912 of the machine will again exhibit the grand total of 5 all of the items in all of the columns; and such grand total may again be printed from the regular adding wheels in the usual manner, for the purpose of comparison and justification with the grand total previously 10 printed. In the printing of these grand totals from the regular adding wheels of the machine, in the usual manner, the swinging frame or bail carrying the accumulators at the rear of the machine may be swung 15 backward and the accumulator pinions maintained out of engagement with the supplemental racks, so that these accumulators will not be affected by the taking of the total from the regular adding wheels.

20 If it be desired to print the total at the foot of each column as soon as the listing of the items in that particular column is completed, this may be done by means of the key 40 in the manner heretofore described, 25 in which event the amount of such total may be permitted to accumulate upon the regular adding wheels, or proper precaution may be taken to prevent it. Thus, to prevent it, the regular total key 265 of the machine may be 30 so manipulated that the pinions 916 of the regular adding wheels 912 will be held out of engagement with the racks 610 during both the downward and upward movement of the latter, so that said pinions and the 35 adding wheels 912 will not be affected by the printing of the total at the foot of any given column by means of the accumulator pinions corresponding to such column. If no precaution be taken to prevent 40 the totals being accumulated upon the regular adding wheels of the machine they will be so accumulated, and when the total of the last listed column has been printed at the foot of such column the regular adding 45 wheels will therefore exhibit twice the amount of the grand total of the items in all of the columns, the items having been first individually accumulated upon said adding wheels and having been again accumulated upon them in the printing of the 50 totals of the respective columns.

In the use or operation of my machine thus far described I have assumed that a single vertical column of items is first listed, 55 and then a second column, and then a third, and so on up to the maximum capacity of the machine, the total of the items in each column being accumulated upon the accumulator corresponding to such column, and a 60 grand total of all of the items being accumulated in the regular accumulator of the machine. The machine may, however, be used for what may be termed "cross-addition", 65 in which case the first item in the first column may be printed in proper position

and the amount of it added upon the corresponding accumulator. Then the paper carriage may be shifted to position to bring the second columnar space upon the paper to the printing point and the second set of accumulators 70 pinions into register with the racks, and the first item in the second column be then listed and added upon the second accumulator; and so on with a series of items in a horizontal line in the several successive 75 columns. When one horizontal line of items has been thus listed the paper carriage may be set back to right hand position, and a second item be listed in the first column and added upon the corresponding accumulator, 80 and the paper carriage be then shifted for the listing of the second item in the second column and the addition of it upon the second accumulator, and so on, with the result that when the bottom of the sheet of paper 85 is reached a series of vertical columns of items will have been listed, and the total of the items in each column will have been accumulated upon the corresponding accumulator, as under the other mode of use 90 and operation of the machine which has been described. When the machine is used for cross-addition, however, the total of each horizontal line of items is to be accumulated, and is to be printed at the right hand end 95 of the line, and in such case I employ the right hand set of accumulator pinions for the purpose of accumulating these line-totals, so that the machine has capacity for one less column of individual items than 100 where it is not used for cross addition. When the machine is thus used for cross-addition the individual items in each horizontal line are accumulated upon the regular adding wheels 912 of the machine as 105 they are individually listed and added upon the corresponding accumulators, so that when the end of the horizontal line is reached the regular adding wheels 912 exhibit the total of the items listed in such 110 horizontal line. This total is then transferred to the right hand set of accumulator pinions, and the adding wheels 912 cleared, by operating the machine to take and print a total in the usual manner, such total being 115 printed at the right hand end of the line and the amount of it being accumulated upon the right hand set of pinions in the same manner as if it had been an item set up on the keyboard of the machine. This operation is repeated at the end of each horizontal line, with the result that when the last item to be listed upon the sheet has been printed in the last column the sheet will bear a series (in the present instance six) of vertical columns of individual items, and a single column of line-totals; while each of the accumulators including the accumulator of the right hand line-total column, will 125 have accumulated upon it the total of the 130

items in the corresponding column. When this has been done a grand total may be immediately printed at the foot of the right hand column by operating the machine in connection with the key 40 in the manner heretofore described, such total being printed from the right hand set of accumulator pinions. This would leave the remaining columns, at the left, containing the individual items, without any footings, and these footings may then be successively printed in the manner heretofore described, and the amounts be permitted to accumulate upon the wheels 912, with the result that when the footing of the right hand or sixth column of individual items has been printed the regular adding wheels 912 of the machine will have accumulated upon them a grand total of all of the items in the six columns, and this grand total should of course correspond with the grand total previously printed from the right hand set of accumulator pinions. The work will thus prove itself, so to speak, and the grand total printed at the lower right hand corner of the sheet of paper will represent at once the total of the series of items or amounts in the vertical line-total column at the right hand side of the sheet of paper, and the total of the footings of the other six columns in the horizontal line at the bottom of the sheet of paper.

A machine equipped with my invention may be employed in still other ways, for obtaining other and different results, according to the desire of the operator and the character of the work to be done, of which it will suffice to cite a single illustration. If it be desired to employ the machine for the purpose of listing several successive series of items, and printing the total of each of such series at the end thereof and clearing the machine preparatory to printing the items in the next series, while at the same time carrying in the machine a total of all of the individual items listed, so that at the end of the operation a grand total of all of the items in all of the series may be printed, such work may be done in the following manner: The regular adding wheels 912 of the machine will in such case be employed for accumulating and printing the totals of the several series of items, and some one of the sets of accumulator pinions 5 will be employed for accumulating the grand total of all of the items. Thus, assuming any one set of said accumulator pinions 5 to be in registry with the racks 1 (or assuming the machine to be provided with only a single set of said pinions), the grand total of all of the items listed may be accumulated upon said pinions in either one of two ways, while the totals of the several series of items are independently accumulated upon the regular adding wheels 912 and printed therefrom. If the machine

be operated in the ordinary way, by simply setting up the amount of each item upon the keyboard and then operating the handle of the machine as usual, it will be understood that each item will be added both upon the regular adding wheels 912 and upon the accumulator pinions 5 in registry with the racks 1, in the manner hereinbefore described. A series of items may be listed and accumulated upon both sets of wheels in this manner, and the total of them be then printed at the foot of the series, and the regular adding wheels 912 be cleared, by operating the machine in the usual well known manner for the taking of a total and clearing the machine. At the taking of such total and clearing of the regular adding wheels the swinging frame or bail carrying the accumulator pinions 5 will be swung backward, to hold said pinions out of mesh with the racks 1, so that the latter will move idly up and down without turning said pinions, and thereby leave accumulated upon said pinions the total of the first series of items listed. This may be done by hand, or by a suitable connection with the regular total key of the machine, or the same result may be accomplished by depressing the key 40 at the end of the forward stroke of the operating handle and holding it depressed during its return stroke. These operations may be repeated indefinitely, the footing of each series of items being printed from the regular adding wheels 912 of the machine, while a total of all the items remains accumulated upon the pinions 5. At the end of the operation or series of operations a grand total of all the items may be printed from said pinions 5 by operating the machine in connection with the key 40 in the manner heretofore explained.

Another way of accomplishing the same result is to maintain the accumulator pinions 5 out of coöperation with the racks 1 during the listing of the individual items, and permit them to coöperate with said racks only during the printing of the totals of the several series of items; in which case such totals will be accumulated upon the pinions 5, so that at the end of operations said pinions will have accumulated upon them all of the totals of the several series of items, and thus exhibit a grand total of all the items, from which such a total may be printed in the manner explained.

When the machine is used for cross-addition, in the manner heretofore described, the regular automatic line-spacing mechanism of the machine, by which the sheet of paper is automatically advanced one line space at each operation of the machine, will be disabled or held out of operation by suitable means. The line spacing may then be effected by turning the platen manually after listing each horizontal line of items,

or the paper may be automatically advanced one line space after the printing of the line-total at the end of each horizontal line by means similar to that illustrated and described in my other pending application, Serial No. 207,631, filed May 12, 1904, (Patent No. 1,028,133 issued June 4, 1912) or by other suitable means.

It remains now to describe the transfer or carrying mechanism which I have provided for the accumulators 5, by means of which, when any pinion in any given accumulator has completed a revolution the next higher pinion in the series is advanced one step in the usual manner. The mechanism which I employ for this purpose is quite similar in operation to, although different in form from, the mechanism provided for the same purpose in connection with the regular accumulators or adding wheels 912 of the Burroughs machine. It is best shown in Figs. 1, 3, 4, 5, 6 and 7. Referring to Fig. 5, it will be seen that the supplemental or secondary racks 1, which operate the accumulators 5, are normally held separated from their carrying levers 611, against the stress of the springs 4, by means of pawls 18 hung upon the shaft 500 and provided with depending hooked arms 18^b engaging shoulders 1^b upon the forward edges of the rack plates. If the hook 18^b of any pawl be disengaged from the corresponding rack, in the position of the parts shown, the spring 4 will pull the rack downward one step, to its limit of movement, and consequently turn forward one step the particular pinion engaged by such rack. Each pinion 5 is provided upon its side with a trip-arm 17 projecting beyond the teeth of the pinion, and these trip arms 17 are adapted to coöperate with the rearwardly projecting arms of the pawls 18. When any pinion completes a revolution its trip-arm 17 will contact with and depress the rearwardly projecting arm of the corresponding pawl 18, and throw its depending hooked arm 18^b forward, thereby disengaging such hooked arm from the corresponding rack plate if the latter be at the time in normal position. Inasmuch, however, as the rack plates are frequently out of normal position when the pinions complete their revolutions and operate the pawls 18 in the manner described, it is necessary to provide means for holding the pawls 18 in their moved positions until the rack plates return to normal position. For this purpose I employ a series of latches 20 hung upon a shaft 22 and provided with rearwardly extending notched or hooked arms 20^a adapted to coöperate with hooks 18^c formed upon the pawls 18. Coiled springs 19 connecting the latches 20 with the pawls 18 serve to engage the latches with the hooks 18^c whenever the pawls 18 are operated by the trip arms 17.

At each operation of the machine, when

the type-carrying and arm-carrying levers 611 are lifted their rear ends rise through one step of movement before the corresponding racks 1 are moved from normal position, this being due to the fact that the pawls 18 normally hold the racks 1 separated from the levers 611 by such distance, against the stress of the springs 4. When the rear ends of the levers rise, therefore, the springs 4 (and the gravity of the racks) hold the racks 70 in normal position until such lost motion is taken up, whereupon the racks are then carried on upward by and with the levers. Under the construction and arrangement of parts which has been described, the lifting 75 of the racks will carry their lugs or shoulders 1^b upward away from the hooks 18^b of the pawls 18, the latter remaining at rest or unaffected by such lifting of the racks. During such upward movement of the racks 80 the accumulator pinions 5 will ordinarily be swung rearward, out of engagement with the racks, as heretofore explained, but will be swung forward and engaged with the racks prior to the return downward movement 85 of the latter. If now during such return downward movement of the racks, and consequent turning of the pinions engaged by them, any given pinion be turned past its point of complete revolution its trip arm 17 90 will contact with and depress the rearwardly projecting arm of the corresponding pawl 18, thereby swinging the depending arm of said pawl forward and carrying its hook 18^b out of the path of the return movement of 95 the lug or shoulder 1^b upon the rack which coöperates with the next higher pinion in the series, and the pawl will be held in such moved position by its latch 20, as heretofore described. When such rack, in its return 100 movement, reaches its normal position it will not be arrested (as usual) by the engagement of its lug 1^b with the hook 18^b of the pawl 18, because the latter has been swung out of its path and is held by the corresponding latch 20. Such rack will therefore move 105 on downward with its lever 611, one step beyond normal position, and thereby advance the pinion meshing with it one extra step to effect the transfer.

For the purpose of tripping all of the latches 20 at each operation of the machine, to permit the operated pawls 18 to return to normal position after having been moved by the trip arms 17 of the pinions, I provide 110 a tripping bar 23 which overlies, and in the present instance is provided with notches 23^a to embrace, the rearwardly projecting arms of the latches 20. As best shown in Fig. 6, this notched bar 23 is hung at its opposite ends in a pair of side arms 24, which are secured at their forward ends to the rock shaft 22 upon which the latches 20 are hung. This shaft 22 is rocked at each operation of the machine by a bell crank 25 hung upon 115

120
125
130

the shaft 801. As best shown in Fig. 4, the upper end of the rearwardly curved arm of this bell crank is pivoted at 26 to the right hand one of the two side arms 24 which carry the trip bar 23, while the depending vertical arm of the bell crank projects into the path of movement of the shaft or rod 704 carried by the arms 711 mounted at their lower ends upon the shaft 703. The rod 704 is the rod which carries the tripping pawls of the printing mechanism in the regular Burroughs machine, and is swung forward at each operation of the machine, and in the present instance contacts with the depending arm 27 of the bell crank 25 and swings its rearwardly curved arm slightly downward, thereby depressing the trip bar 23 and with it the rearwardly projecting horizontal arms of all of the latches 20 and disengaging their hooked rear ends from any of the pawls 18 that may have been engaged therewith, this operation occurring at the proper time to permit the pawls 18 to resume their normal position for coöperation with the shoulders 25 on the rack plates. The trip bar 23 and associated parts are yieldingly held in and returned to their normal positions by a spring 28 connected at its upper end to a fixed point and at its lower end to a depending curved arm 27 projecting from one of the side arms 24 which carry the trip bar 23.

The pawls 18 not only perform the function which has been explained, but their rear ends 18^a in the present instance serve as stops to arrest the accumulator pinions at zero position when they are turned backward in the taking of a total, as heretofore described, the abrupt sides of the trip arms 17 at such time contacting with the rear ends 40 of the pawls 18 and arresting the pinions at the proper point.

I claim:

1. A machine for listing items in a plurality of columns side by side and printing the total of each column at the foot thereof, comprising printing devices for listing the items in the several columns, a paper carriage for supporting a sheet of paper and moving it transversely of the machine to bring successive vertical columns thereof opposite the printing type, a plurality of sets of accumulator pinions mounted upon said paper carriage, one set for each of the several columns of items to be listed, means for accumulating upon each set of pinions the items of the corresponding column as said items are listed, and means for causing the return of any set of pinions to zero position to set up the type to print the total of the corresponding column of items at the foot thereof.

2. A machine for listing items in a plurality of columns side by side and printing the total of each column at the foot thereof and also a grand total of all of the items in

all of the columns, comprising printing devices for listing the items in the several columns, a plurality of sets of accumulator pinions, one set for each of the several columns of items to be listed, means for accumulating upon each set of pinions the items of the corresponding column as they are listed, another set of accumulator pinions with means for accumulating upon them all of the items in all of the columns, means for causing the return of any of the first mentioned sets of accumulator pinions to zero position to set up the type to print the total of the corresponding column of items at the foot thereof, and means for causing the return of the other set of pinions to zero position to set up the type to print a grand total of all of the items in all of the columns.

3. A machine for listing items in horizontal lines across a sheet of paper and printing the total of the items in each line at the end thereof and for printing a grand total of the line-totals at the end of operations, comprising printing devices for listing the items, a set of accumulator pinions with means for accumulating upon them the items in each horizontal line as listed, a second set of accumulator pinions, means for causing the return of the first mentioned set of pinions to zero position at the end of each line of items to set up the type to print the total of said line and to transfer said total to the second set of accumulator pinions, whereby the totals of successive horizontal lines of items may be accumulated upon said second set of pinions, and means for causing the return of said second set of pinions to zero position at the end of operations to set up the type for printing a total of all of the line-totals accumulated upon said pinions.

4. A machine for listing items in horizontal lines and vertical columns and printing the line totals at the ends of the horizontal lines and the column totals at the foot of the several columns, comprising printing devices for listing items in the several columns, a set of accumulator pinions upon which the items in each horizontal line are accumulated, a plurality of sets of accumulator pinions corresponding to the several vertical columns of items to be listed, a set of line-total accumulator pinions, means for causing each item as listed to be accumulated upon the first mentioned set of accumulator pinions and also upon the set of pinions corresponding to the vertical column in which such item is listed, means for causing the return of the first mentioned set of accumulator pinions to zero position to set up the type to print the line-total accumulated thereon and to transfer such line-total to the line-total set of accumulator pinions, and means for causing the return to zero position of any set of pinions corresponding to any one of the vertical columns or the

line-total column to set up the type to print the total of such column at the foot thereof, whereby the amount printed at the foot of the line-total column by means of the line-total accumulator pinions will represent the total of the line-total column of items and also the total of the footings of the several other vertical columns of items.

5. A machine for listing items in several successive series and printing the total of each series at the end thereof and a grand total of all of the items at the end of all of the series, comprising printing devices for listing the individual items, a set of accumulator pinions and means for accumulating upon said pinions the individual items of each series as listed, a second set of accumulator pinions, means for causing the return of the first-mentioned set of pinions to zero 20 position at the end of any series of items to set up the type to print the total of such series of items and to transfer such total to the second set of pinions, and means for causing the subsequent return of said second 25 set of pinions to zero position to set up the type to print the grand total of all the series-totals accumulated upon such second set of pinions.

6. In an adding and listing machine, the combination, with means for listing a series of items and an accumulator for accumulating the total thereof, and a total key and connections by depressing which key and operating the machine the total of the series 30 of items may be printed and the accumulator be cleared or reset to zero, of a supplemental accumulator, means for transferring to said accumulator the totals of several series of items as said totals are successively 35 printed at the ends of the respective series, so as to thereby accumulate upon said supplemental accumulator a grand total of all of the items in the several series, and a supplemental total key and connections by depressing which key and operating the machine such grand total may be printed from 40 said supplemental accumulator and the accumulator be cleared.

7. In an adding machine, the combination, 50 with the usual adding mechanism thereof, and the series of sector bars or levers for operating the same, of a series of independent accumulators arranged to be operated one at a time by the sector bars for accumulating separate lists or columns of items, and a frame shiftable transversely of the machine, and arranged to carry said series of accumulators whereby any one thereof may be placed in operative relationship with the sector bars.

8. In an adding machine, the combination, 55 with the usual adding mechanism thereof and the series of sector bars or levers for operating the same, of a series of independent accumulators arranged to be operated

one at a time by the sector bars for accumulating separate lists or columns of items, and a frame in which the accumulators are mounted, said frame being shiftable transversely of the machine and also having a 70 rocking movement to rock any one of the accumulators into and out of operative relationship with the machine.

9. In an adding machine, the combination, 75 with the usual adding mechanism thereof and the series of sector bars or levers for operating the same, of a series of independent accumulators arranged to be operated one at a time by the sector bars for accumulating separate lists or columns of items, 80 and a frame in which the accumulators are mounted, said frame being shiftable transversely of the machine and also having a rocking movement to rock any one of the accumulators into and out of operative relationship with the machine, and means under the control of the machine in its operations for so rocking the frame.

10. In an adding machine, the combination, 85 with the usual adding mechanism thereof and the series of sector bars or levers for operating the same, of a series of movable racks under the control of the bars or levers and having a movement independent of the latter equal to the value of one tooth, a series of independent accumulators arranged to 90 coöperate with the racks for separately accumulating items, and transfer mechanism coöperating with the accumulators and the racks and arranged to control said independent movement of the latter.

11. In an adding machine, the combination, 95 with the usual adding mechanism thereof and the series of sector bars or levers for operating the same, of a series of movable racks under the control of the levers and having a pin and slot connection therewith, a series of independent accumulators arranged to coöperate with the racks for separately accumulating items, and transfer mechanism 105 coöperating with the accumulators and the racks and normally holding the latter away from their levers.

12. In an adding machine, the combination, 110 with the usual adding mechanism thereof and the series of sector bars or levers for operating the same, of a series of movable racks under the control of the levers and having a pin and slot connection therewith, a series of independent accumulators arranged to coöperate with the racks for separately accumulating items, a spring connection between each rack and its lever and tending to draw the former toward the latter, and transfer mechanism coöoperating 115 with the accumulators and the racks and normally holding the latter away from their levers against the tension of said springs.

13. In an adding machine, the combination, 120 with the usual adding mechanism there-

- of and the series of sector bars or levers for operating the same, of a series of movable racks under the control of the levers and held toward the latter with a yielding pressure, 5 a series of independent accumulators arranged to coöperate with the racks for separately accumulating items, and transfer mechanism coöperating with the accumulators and the racks and normally holding the 10 latter away from their levers.
14. In an adding machine, the combination, with the usual adding mechanism thereof and the series of sector bars or levers for operating the same, of a series of movable racks under the control of the levers and held toward the latter with a yielding pressure, a series of independent accumulators arranged to coöperate with the racks for separately accumulating items, a series of carrying pawls coöperating with the racks to hold them away from their levers against 15 said pressure, and transfer arms or pawls coöperating with the accumulators to actuate the carrying pawls to release a rack or 20 racks and thereby carry one to the particular accumulator in service.
15. In an adding machine, the combination, with the usual adding mechanism thereof and the series of sector bars or 30 levers for operating the same, of a series of movable racks operatively connected with the levers and held theretoward by spring pressure, a corresponding series of carrying pawls for normally holding the racks away 35 from their levers against said spring pressure, a series of accumulators arranged to coöperate, one at a time, with the racks, and transfer arms or pawls carried by each accumulator to coöperate with the carrying pawls in the operation of 40 carrying one.
16. In an adding machine, the combination, with the usual adding mechanism thereof and the series of sector bars or levers for operating the same, of a series of movable racks operatively connected with the levers and held theretoward by spring pressure, a corresponding series of carrying pawls each having a hook to normally engage 45 its rack and thereby hold it away from its lever, a series of accumulators arranged to coöperate, one at a time, with the racks, and transfer arms or pawls carried by each accumulator to coöperate with the carrying pawls in the operation of 50 carrying one.
17. In an adding machine, the combination, with the usual adding mechanism thereof and the series of sector bars or levers for operating the same, of a series 55 of movable racks operatively connected with the levers and held theretoward by spring pressure, said racks each having a projection, a corresponding series of carrying pawls each having a hook to normally engage 60 the projection of its rack and there-
- by hold the latter away from its lever, a series of accumulators arranged to coöperate, one at a time, with the racks, and transfer arms or pawls carried by each accumulator to coöperate with the carrying pawls 65 in the operation of carrying one.
18. In an adding machine, the combination, with the usual adding mechanism thereof and the series of sector bars or levers for operating the same, of a series of movable racks operatively connected with the levers and held theretoward by spring pressure, said racks each having on one edge a tooth, a corresponding series of carrying pawls each having a hook normally engaging the tooth of its racks to thereby hold the latter away from its lever, a series of accumulators arranged to coöperate, one at a time, with the racks, and transfer arms or pawls carried by each accumulator to coöperate with the carrying pawls in the operation of carrying one.
19. In an adding machine, the combination, with the usual adding mechanism thereof and the series of sector bars or levers for operating the same, of a series of movable racks operatively connected with the levers and held theretoward by spring pressure, a corresponding series of carrying pawls for normally holding the racks away 90 from their levers against said spring pressure, a series of detents for detaining the carrying pawls in their operated position, means controlled by the machine in its operation for restoring the detents and releasing the carrying pawls, a series of accumulators arranged to coöperate, one at a time, with the racks, and transfer arms or pawls carried by each accumulator to coöperate with the carrying pawls in the operation of 95 carrying one.
20. In an adding machine, the combination, with the usual adding mechanism thereof and the series of sector bars or levers for operating the same, of a series of movable racks operatively connected with the levers and held theretoward by spring pressure, a corresponding series of carrying pawls for normally holding the racks away 100 from their levers against said spring pressure, a series of detents for detaining the carrying pawls in their operated position, a bail controlled by the machine in its operation for restoring the detents and releasing the carrying pawls, a series of accumulators 105 arranged to coöperate, one at a time, with the racks, and transfer arms or pawls carried by each accumulator to coöperate with the carrying pawls in the operation of carrying one.
21. In an adding machine, the combination, with the usual adding mechanism thereof and the series of sector bars or levers for operating the same, of a series of movable racks operatively connected with 110

the levers and held theretoward by spring pressure, a corresponding series of carrying pawls for normally holding the racks away from their levers against said spring pressure, said carrying pawls being spring pressed to hold their racks, a series of detents for detaining the carrying pawls in their operated position, a bail controlled by the machine in its operation for restoring the detents and releasing the carrying pawls, a series of accumulators arranged to coöperate, one at a time, with the racks, and transfer arms or pawls carried by each accumulator to coöperate with the carrying pawls in the operation of carrying one.

22. In an adding machine, the combination, with the usual adding mechanism thereof and the series of sector bars or levers for operating the same, of a series of movable racks operatively connected with the levers and held theretoward by spring pressure, a corresponding series of carrying pawls for normally holding the racks away from their levers against said spring pressure, said carrying pawls being spring pressed to hold their racks, a series of detents for detaining the carrying pawls in their operated position, a bail controlled by the machine in its operation for restoring the detents and releasing the carrying pawls, a series of accumulators arranged to coöperate, one at a time, with the racks, transfer arms or pawls carried by each accumulator to coöperate with the carrying pawls in the operation of carrying one, and an operating arm connected with the bail and arranged in the path of movement of a movable part of the machine.

23. In an adding machine, the combination, with the usual adding mechanism thereof and the series of sector bars or levers for operating the same, of a series of movable racks operatively connected with the levers and held theretoward by spring pressure, a corresponding series of carrying pawls for normally holding the racks away from their levers against said spring pressure, said carrying pawls being spring pressed to hold their racks, a series of detents for detaining the carrying pawls in their operated position, a bail controlled by the machine in its operation for restoring the detents and releasing the carrying pawls, a series of accumulators arranged to coöperate, one at a time, with the racks, transfer arms or pawls carried by each accumulator to coöperate with the carrying pawls in the operation of carrying one, and a bell crank one arm of which is connected with the bail and the other of which is arranged in the path of movement of a movable part of the machine.

24. In an adding machine, the combination, with the usual adding mechanism thereof and the series of sector bars or levers for

operating the same, of a series of racks operatively connected with the levers and each having a slot on its arc of movement, a transverse rod passing through the slots, and a series of independent accumulators arranged to coöperate, one at a time, with said racks.

25. In an adding machine, the combination, with the usual adding mechanism thereof and the series of sector bars or levers for operating the same, of a series of racks operatively connected with the levers and each having a slot in its arc of movement, a transverse rod passing through the slots to guide the racks, a series of carrying pawls strung on such rod and arranged to coöperate with the racks, and a series of independent accumulators arranged to coöperate, one at a time, with said rack, each accumulator comprising a plurality of pinions having transfer pawls adapted to coöperate with said carrying pawls in the operation of carrying one.

26. In an adding machine, the combination, with the usual adding mechanism thereof, of a longitudinally movable carriage, of a frame arranged to rock on said carriage, and a series of accumulators mounted in said frame and arranged to be operated through connection with the actuator instrumentalities of said usual adding mechanism.

27. In an adding machine, the combination, with the usual adding mechanism thereof, of a longitudinally movable carriage, of a frame arranged to rock on said carriage, and controlled in its rocking movements by the machine in its operations, and a series of accumulators mounted in said frame and arranged to be operated through connection with the actuator instrumentalities of said usual adding mechanism.

28. In an adding machine, the combination, with the usual adding mechanism thereof, of a longitudinally movable carriage, of a frame arranged to rock on said carriage, a transverse rod or shaft in such rocking frame, and a series of accumulators mounted on said rod and arranged to be operated through connection with the actuator instrumentalities of said usual adding mechanism.

29. In an adding machine, the combination, with the usual adding mechanism thereof, of a longitudinally movable carriage, of a frame arranged to rock in said carriage, means for limiting the rocking movement of such frame, a transverse rod or shaft in such rocking frame, and a series of accumulators mounted on said rod and arranged to be operated through connection with the actuator instrumentalities of said usual adding mechanism.

30. In an adding machine, the combination, with the usual adding mechanism thereof, of a longitudinally movable car-

- riage, of extension plates on said carriage, a frame arranged to rock between said plates, a transverse rod or shaft in such rocking frame, and a series of accumulators 5 mounted on said rod and arranged to be operated through connection with the actuator instrumentalities of said usual adding mechanism.
31. In an adding machine, the combination, with the usual adding mechanism thereof, of a longitudinally movable carriage, of extension plates on said carriage, a frame arranged to rock between said plates, stops on the plates to limit the degree of rocking of the frame, a transverse rod or shaft in the latter and a series of accumulators mounted on said rod and arranged to be operated through connection with the actuator instrumentalities of said usual adding mechanism.
32. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, and means for normally locking such pinions.
33. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, and a corresponding series of locking plates or pawls mounted on the carriage and arranged to coöperate with the pinions.
34. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, a corresponding series of locking plates or pawls arranged to coöperate with the pinions, and a rod on the carriage on which the series of locking plates are mounted to independently rock.
35. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, a corresponding series of locking plates or pawls normally spring pressed to engage and lock their pinions, said accumulators, a series of accumulators mounted on said rod and each comprising a plurality of pinions arranged to be operated through connection with the actuator instrumentalities of said usual adding mechanism, a corresponding series of locking plates or pawls arranged to coöperate with the pinions, and means for normally holding such locking plates in engagement with the pinions.
36. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, and a corresponding series of locking plates normally spring pressed to engage and lock their pinions.
37. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, and a corresponding series of locking plates normally arranged to engage and lock their pinions, each member of the series being independently operable.
38. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, a corresponding series of locking plates normally spring pressed to engage and lock their pinions and means for disengaging the particular member of the series of locking plates from engagement with the particular accumulator then in action.
39. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, a corresponding series of locking plates or pawls normally spring pressed to engage and lock their pinions, said accumulators, a series of accumulators mounted on said rod and each comprising a plurality of pinions arranged to be operated through connection with the actuator instrumentalities of said usual adding mechanism, a corresponding series of locking plates or pawls normally spring pressed to engage and lock their pinions, said accumulators, a series of accumulators mounted on said rod and each comprising a plurality of pinions arranged to be operated through connection with the actuator instrumentalities of said usual adding mechanism, a corresponding series of locking plates or pawls arranged to coöperate with the pinions, and means for normally holding such locking plates in engagement with the pinions.

lators being arranged to be presented, one at a time, to the machine for action, and means for automatically disengaging the locking plates or pawls of an accumulator when presented for action without affecting the locking plates of the other accumulators.

40. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, a corresponding series of locking plates or pawls normally spring pressed to engage and lock their pinions, and an arm arranged in the path of movement of the locking plates of any one of the accumulators when presented for action to the machine.

41. In an adding machine, the combination, with the usual adding mechanism thereof, of a longitudinally movable carriage, of a frame arranged to rock on the carriage, a transverse rod or shaft in such rocking frame, a series of accumulators mounted on said rod and each comprising a plurality of pinions arranged to be operated through connection with the actuator instrumentalities of said usual adding mechanism, a corresponding series of locking plates or pawls in the form of pivoted bails or frames normally spring pressed into engagement with their respective accumulators and an arm arranged in the path of movement of the bails when their accumulators are presented for action to the machine.

42. In an adding machine, the combination, with the adding and printing mechanism thereof and with its longitudinally movable paper carriage, of a platen mounted in the carriage and with which the printing mechanism coöperates, and a series of accumulators mounted on said paper carriage above the platen and arranged to be operated through connection with the actuator instrumentalities of said usual adding mechanism for separate accumulations.

43. In an adding machine, the combination, with the usual adding mechanism thereof, of a frame having a transverse and longitudinal movement with respect to the machine, a series of accumulators mounted on said frame and arranged to be operated through connection with the actuator instrumentalities of said usual adding mechanism, and means for rocking the frame.

44. In an adding machine, the combination, with the usual adding mechanism thereof, of an independent accumulator arranged to be rocked in and out of operative relationship with the actuator instrumentalities of said usual adding mechanism,

means for rocking the accumulator, and means for reversing the order of the rocking movements thereof, when a total is transferred from the accumulator to the machine.

45. In an adding machine, the combination, with the usual adding mechanism thereof, of an independent accumulator arranged to be rocked in and out of operative relationship with the actuator instrumentalities of said usual adding mechanism, means for rocking the accumulator, and means under the control of the operator for reversing the order of the rocking movements thereof when a total is transferred from the accumulator to the machine.

46. In an adding machine, the combination, with the usual adding mechanism thereof, of an independent accumulator arranged to be rocked in and out of operative relationship with the actuator instrumentalities of said usual adding mechanism, means for rocking the accumulator, and key-controlled means for reversing the order of the rocking movements thereof, when a total is transferred from the accumulator to the machine.

47. In an adding machine, the combination, with the usual adding mechanism thereof, of a series of independent accumulators arranged to be operated through connection with the actuator instrumentalities of said usual adding mechanism, a rocking frame in which said accumulators are mounted, means for rocking said frame, and means under the control of the operator for reversing the order of the rocking movements thereof when a total is transferred from any accumulator to the machine.

48. In an adding machine, the combination, with the usual adding mechanism thereof, of a series of independent accumulators arranged to be operated through connection with the actuator instrumentalities of said usual adding mechanism, a rocking frame in which said accumulators are mounted, said frame being held in one direction with a yielding pressure to present its accumulators one at a time to the machine, an operating arm, and means for rocking said frame against its yielding pressure.

49. In an adding machine, the combination, with the usual adding mechanism thereof, of a series of independent accumulators arranged to be operated through connection with the actuator instrumentalities of said usual adding mechanism, a rocking frame in which said accumulators are mounted, said frame being held in one direction with a yielding pressure to present its accumulators one at a time to said actuator instrumentalities, and an operating arm adapted to move said frame against such yielding pressure.

50. In an adding machine, the combination, with the usual adding mechanism,

- thereof, of a series of independent accumulators arranged to be operated through connection with the actuator instrumentalities of said usual adding mechanism, a rocking 5 frame in which said accumulators are mounted, a rocking arm arranged to rock said frame, a rocking lever connected with said arm, and an actuating arm or bar operatively connected with the rocking lever.
- 10 51. In an adding machine, the combination, with the usual adding mechanism thereof, of a series of independent accumulators arranged to be operated through connection with the actuator instrumentalities 15 of said usual adding mechanism, a rocking frame in which said accumulators are mounted, a rocking arm arranged to rock said frame, a rocking lever connected with said arm, and an actuating arm or bar ar- 20 ranged to be operatively connected with the rocking lever at different points on the latter at the will of the operator.
52. In an adding machine, the combination, with the usual adding mechanism thereof, of a series of independent accumulators arranged to be operated through connection with the actuator instrumentalities of said usual adding mechanism, a rocking frame in which said accumulators are 25 mounted, a rocking arm arranged to rock said frame, a rocking lever connected with said arm, and a bifurcated actuating arm or bar, one or the other of whose forks is ar- 30 ranged to be operatively connected with the 35 rocking lever at one or the other sides of its pivotal point.
53. In an adding machine, the combination, with the usual adding mechanism thereof, of a series of independent accumu- 40 lators arranged to be operated through connection with the actuator instrumentalities of said usual adding mechanism, a rocking frame in which said accumulators are mounted, a rocking arm arranged to rock 45 said frame, a rocking lever connected with said arm, pins or studs on the rocking lever, and a bifurcated actuating arm or bar one or the other of whose forks is arranged to en- 50 gage one of the pins or studs.
54. In an adding machine, the combination, with the usual adding mechanism thereof, of a series of independent accumulators arranged to be operated through connection with the actuator instrumentalities 55 of said usual adding mechanism, a rocking frame in which said accumulators are mounted, said frame being held in one direction with a yielding pressure to present its accumulators, one at a time, to the actu- 60 ators, a rock arm for operating said frame, and a key-controlled actuating arm or bar operatively connected with the rock arm.
55. In an adding machine, the combination, with the usual adding mechanism thereof, of a series of independent accu- 65
- mulators arranged to be operated through connection with the actuator instrumentalities of said usual adding mechanism, a rocking frame in which said accumulators are mounted, said frame being held in one direction with a yielding pressure to present its accumulators, one at a time, to the actu- 70 ators, a rock arm for operating said frame, an actuating arm or bar operatively connected with the rock arm, and a pivoted arm arranged to reciprocate the bar and thereby operate said rock arm.
56. In an adding machine, the combination, with the usual adding mechanism thereof, of a series of independent accumulators arranged to be operated through connection with the actuator instrumentalities of said usual adding mechanism, a rocking frame in which said accumulators are mounted, said frame being held in one direction with a yielding pressure to present its accumulators, one at a time, to the actu- 75 ators, a rock arm for operating said frame, an actuating arm or bar operatively connected with the rock arm, and a pivoted arm arranged to reciprocate the bar and thereby operate said rock arm.
57. In an adding machine, the combination, with the usual adding mechanism thereof, of a series of independent accumulators arranged to be operated through connection with the actuator instrumentalities of said usual adding mechanism, a rocking frame in which said accumulators are 80 mounted, said frame being held in one direction with a yielding pressure to present its accumulators, one at a time, to the actu- 85 ators, a rock arm for operating said frame, an actuating arm or bar operatively connected with the rock arm, and having a re- 90 cess or notch, and a pivoted arm having a pin or stud arranged to operate in said recess and thereby reciprocate the bar.
58. In an adding machine, the combination, with the usual adding mechanism thereof, of a series of independent accumulators arranged to be operated through connection with the actuator instrumentalities of said usual adding mechanism, a rocking frame in which said accumulators are 95 mounted, said frame being held in one direction with a yielding pressure to present its accumulators, one at a time, to the machine, a rock arm for operating said frame, an actuating arm or bar operatively connected with the rock arm, and having a re- 100 cess or notch, and a spring pressed pivoted arm having a pin or stud arranged to operate in said recess and thereby reciprocate the bar.
59. In an adding machine, the combination, with the usual adding mechanism thereof, of a series of independent accumulators arranged to be operated through connection with the actuator instrumentalities of said usual adding mechanism, a rocking frame in which said accumulators are 105 mounted, said frame being held in one direction with a yielding pressure to present its accumulators, one at a time, to the machine, a rock arm for operating said frame, an actuating arm or bar operatively connected with the rock arm, and having a re- 110 cess or notch, and a pivoted arm having a pin or stud arranged to operate in said recess and thereby reciprocate the bar.
60. In an adding machine, the combination, with the usual adding mechanism thereof, of a series of independent accumulators arranged to be operated through connection with the actuator instrumentalities of said usual adding mechanism, a rocking frame in which said accumulators are 115 mounted, said frame being held in one direction with a yielding pressure to present its accumulators, one at a time, to the machine, a rock arm for operating said frame, an actuating arm or bar operatively connected with the rock arm, and having a re- 120 cess or notch, a pivoted arm having a pin arranged to operate in said recess and thereby reciprocate the bar and a cam plate ar- 125 ranged to rock said pivoted arm and thereby reciprocate the bar.
61. In an adding machine, the combination, with the usual adding mechanism thereof, of a series of independent accumulators arranged to be operated through connection with the actuator instrumentalities of said usual adding mechanism, a rocking frame in which said accumulators are mounted, said frame being held in one direction with a yielding pressure to present its accumulators, one at a time, to the machine, a rock arm for operating said frame, an actuating arm or bar operatively connected with the rock arm, and having a re- 130 cess or notch, a pivoted arm having a pin arranged to operate in said recess and thereby reciprocate the bar.

thereof, of a series of independent accumulators arranged to be operated through connection with the actuator instrumentalities of said usual adding mechanism, a rocking frame in which said accumulators are mounted, a rocking arm arranged to rock said frame, a rocking lever connected with said arm, a bifurcated actuating arm or bar one or the other of whose forks is arranged 5 to engage the rocking lever at the will of the operator, said bar having two communicating notches, and a movable stud coöperating with one or the other of said notches according to the position of the bar to reciprocate the latter.

60. In an adding machine, the combination, with the usual adding mechanism thereof, of a series of independent accumulators arranged to be operated through connection with the actuator instrumentalities of said usual adding mechanism, a rocking frame in which said accumulators are mounted, a rocking arm arranged to rock said frame, a rocking lever connected with 10 said arm, a bifurcated actuating arm or bar one or the other of whose forks is arranged to engage the rocking lever at the will of the operator, said bar having two communicating notches, a pivoted operating arm, and a 15 pin or stud thereon arranged to coöperate with one or the other of said notches according to the position of the bar to reciprocate the latter.

61. In an adding machine, the combination, with the usual adding mechanism thereof, of a series of independent accumulators arranged to be operated through connection with the actuator instrumentalities of said usual adding mechanism, a rocking frame 20 in which said accumulators are mounted, a rocking arm arranged to rock said frame, a rocking lever connected with said arm, a bifurcated actuating arm or bar one or the other of whose forks is arranged to engage 25 the rocking lever at the will of the operator, said bar having two connecting notches, a pivoted arm 34 having a pin or stud arranged to coöperate with one or the other of 30 said notches according to the position of the bar to reciprocate the latter, and a cam plate 38 for actuating the arm 34.

62. In an adding machine, the combination, with the usual adding mechanism thereof, of a series of independent accumulators 35 arranged to be operated through connection with the actuator instrumentalities of said usual adding mechanism, a rocking frame in which said accumulators are mounted, a rocking arm arranged to rock 40 said frame, a rocking lever connected with said arm, a bifurcated actuating arm or bar one or the other of whose forks is arranged to engage 45 the rocking lever at the will of the operator, said bar having two communicating notches, a pivoted arm 34 having a pin or stud arranged to coöperate with one or the other of 50 said notches according to the position of the bar to reciprocate the latter.

pin or stud arranged to coöperate with one or the other of said notches according to the position of the bar to reciprocate the latter, and means under the control of the operator for controlling the position of the bar relative to said arm 34.

63. In an adding machine, the combination, with the usual adding mechanism thereof, of a series of independent accumulators arranged to be operated through connection with the actuator instrumentalities of said usual adding mechanism, a rocking frame in which said accumulators are mounted, a rocking arm arranged to rock said frame, a rocking lever connected with 70 said arm, a bifurcated actuating arm or bar one or the other of whose forks is arranged to engage the rocking lever at the will of the operator, said bar having two communicating notches, a pivoted arm 34 having a pin 75 or stud arranged to coöperate with one or the other of said notches according to the position of the bar to reciprocate the latter, and a special key operatively connected with the box for controlling the position of the 80 same relative to the arm 34.

64. In an adding machine, the combination, with the usual adding mechanism thereof, of a series of independent accumulators arranged to be operated through connection with the actuator instrumentalities of said usual adding mechanism, a rocking frame in which said accumulators are mounted, a rocking arm arranged to rock said frame, a rocking lever connected with 95 said arm, a bifurcated actuating arm or bar one or the other of whose forks is arranged to engage the rocking lever at the will of the operator, said bar having two accumulating notches, a pivoted arm 34 having a pin or 100 stud arranged to coöperate with one or the other of said notches according to the position of the bar to reciprocate the latter, and a key stem pivotally connected with the bar for shifting the position of the latter relative to the arm 34 at the will of the operator.

65. In an adding machine, the combination of a series of main levers, racks carried at one end thereof, an accumulator coöperating therewith, means for normally locking said racks, secondary racks carried at the other end of the levers, a plurality of accumulators coöperating with the latter racks, mechanism arranged to rock the accumulators into and out of coöoperative relation with the secondary racks, and means for controlling said mechanism and said locking means to enable a total to be transferred from any one of the plurality of accumulators to the machine proper.

66. In an adding machine, the combination of a series of main levers, racks carried at one end thereof, an accumulator coöperating therewith, means for normally lock- 130

- ing said racks, secondary racks carried at the other end of the levers, a plurality of accumulators coöperating with the latter racks, mechanism arranged to rock the accumulators into and out of coöperative relation with the secondary racks, and key-actuated means for controlling said mechanism and said locking means to enable a total to be transferred from any one of the plurality of accumulators to the machine proper.
67. In an adding machine, the combination of a series of main levers, racks carried at one end thereof, an accumulator coöperating therewith, means for normally locking said racks, secondary racks carried at the other end of the levers, a plurality of accumulators coöperating with the latter racks, mechanism arranged to rock the accumulators into and out of coöperative relation with the secondary racks, a key stem operatively connected with said mechanism for controlling the same, and a bail controlled by the key stem for operating said locking means to release the first named racks to enable a total to be transferred from any one of the plurality of accumulators to the machine proper.
68. In an adding machine, the combination of a series of main levers, racks carried at one end thereof, detents for normally locking said racks, an accumulator coöperating with the racks, secondary racks carried at the other end of the levers, a plurality of accumulators coöperating with the latter racks, mechanism arranged to rock the accumulators into and out of coöperative relation with the secondary racks, and a special key for controlling said mechanism and for releasing said detents when it is desired to transfer the total from any one of the plurality of accumulators to the machine proper.
69. In an adding machine, the combination of a series of main levers, racks carried at one end thereof, detents for normally locking said racks, an accumulator coöperating with the racks, secondary racks carried at the other end of the levers, a plurality of accumulators coöperating with the latter racks, mechanism arranged to rock the accumulators into and out of coöperative relation with the secondary racks, a special key and stem for controlling said mechanism, and a bail 42 operated by the key stem and adapted to release the detents.
70. In an adding machine, the combination of a series of main levers, racks carried at one end thereof, detents for normally locking said racks, an accumulator coöperating with the racks, secondary racks carried at the other end of the levers, a plurality of accumulators coöperating with the latter racks, mechanism arranged to rock the accumulators into and out of coöperative relation with the secondary racks, a special key and stem for controlling said mechanism, a bail 42 adapted, when rocked, to move the detents and release their racks, and an operating arm 44 connecting between the bail and the key stem for rocking the former.
71. In an adding machine, the combination, of a series of main levers, racks carried at one end thereof, detents for normally locking said racks, an accumulator coöperating with the racks, secondary racks carried at the other end of the levers, a plurality of accumulators coöperating with the latter racks, a special key and stem for controlling said mechanism, a bail 42 adapted, when rocked, to move the detents and release their racks, an arm 44 pivoted at one end to the bail and having a pin near its other end arranged in the path of movement of the key stem.
72. In an adding machine, the combination, of a series of main levers, racks carried at one end thereof, detents for normally locking said racks, an accumulator coöperating with the racks, secondary racks carried at the other end of the levers, a plurality of accumulators coöperating with the latter racks, mechanism arranged to rock the accumulators into and out of coöperative relation with the secondary racks, a special key and stem for controlling said mechanism, and an operating connection between the detents and the key stem for operating the detents and thereby releasing their racks when the key is operated.
73. In an adding machine, the combination, with the adding mechanism thereof, including the usual accumulator, of a series of independent accumulators arranged to coöperate with the actuator instrumentalities of said usual accumulator, one at a time, to accumulate a part or group of the items of which the said usual accumulator accumulates the grand total, and means for transferring the accumulations of any one or more of such series of accumulators to said usual accumulator when the machine is clear.
74. In an adding machine, the combination, of a series of movable bars or levers bearing type at one end, a set of racks operatively connected with each end of the bars or levers, a plurality of accumulators arranged to coöperate, one at a time, with the set of racks at the type end of the lever, and a single accumulator arranged to coöperate with the other set of racks.
75. In an adding machine, the combination, of a series of movable bars or levers, a set of racks carried at one end of such levers, an accumulator in constant coöperation with such racks, a second set of racks operatively connected with the other end of such levers, and arranged above and in sub-

stantially the same plane as the latter, and a series of independent accumulators adapted to coöperate, one at a time, with said second set of racks.

- 5 76. In an adding machine, the combination, of a series of pivoted bars or levers having at one end sectors bearing type, a set of racks operatively connected with the type end of the levers, a series of accumulators arranged to coöperate, one at a time, with said racks, a second set of racks operatively connected with the other end of such levers, and an accumulator arranged to coöperate with said second set of racks.
- 10 77. In an adding machine, the combination, of a series of movable bars or levers, a set of racks carried at one end of such levers, an accumulator in constant coöperation with such racks, a second set of racks operatively connected with the other end of such levers, a longitudinally movable carriage, a rod arranged in such carriage and in rear of said second set of racks, and a series of independently operating accumulators strung on said rod, side by side and arranged to be placed, one at a time, into coöperative relation with said second set of racks.

30 78. In a machine of the character described, the combination of actuators widely spaced apart at one place and closely assembled at another, denominational sets of keys for the actuators respectively coacting with the widely spaced portions thereof, and 35 a plurality of axially alined sets of wheels to coöperate selectively with the closely assembled portions of said actuators.

40 79. In a machine of the character described, the combination of actuators widely spaced apart at one place and closely assembled at another, denominational sets of keys for the actuators respectively coacting with the widely spaced portions thereof, a primary set of accumulator wheels to coöperate with the widely spaced portions of the actuators, and a plurality of sets of wheels to coöperate selectively with the closely assembled portions of said actuators.

50 80. In a machine of the character described, the combination of a denominational series of actuator bars having widely spaced racks at one location and closely spaced racks at another location, gear wheels alined with said widely spaced racks respectively, numeral wheels united with said gear wheels respectively and accommodated by the spacing apart of racks, a set of keys for each actuator, means for variously measuring advance of actuators by selective use 55 of keys, a plurality of sets of axially alined gears, means for selectively establishing co-operative relationship between the same and the closely spaced racks, means for engaging and disengaging the first mentioned 60 racks and gear wheels, and means for en-

gaging and disengaging the closely spaced racks and the selected set of gear wheels of the aforesaid plurality of sets.

81. In a machine of the character described, the combination of a denominational series of actuator bars having widely spaced racks at one location and closely spaced racks at another location, gear wheels alined with said widely spaced racks respectively, numeral wheels united with said gear wheels respectively and accommodated by the spacing apart of racks, a set of keys for each actuator, means for variously measuring advance of actuators by selective use of keys, a plurality of sets of axially alined gears, means for selectively establishing co-operative relationship between the same and the closely spaced racks, means for engaging and disengaging the first mentioned racks and gear wheels, means for engaging and disengaging the closely spaced racks and the selected set of gear wheels of the aforesaid plurality of sets, and a laterally shiftable carriage.

82. In a machine of the character described, the combination of actuators widely spaced apart at one place and closely assembled at another, denominational sets of keys for the actuators respectively coacting with the widely spaced portions thereof, a plurality of axially alined sets of wheels to coöperate selectively with the closely assembled portions of said actuators, and printing devices including types set by closely assembled portions of the actuators, and a laterally shiftable carriage which controls the selection of the set of wheels.

83. In a machine of the character described, the combination of actuators widely spaced apart at one place and closely assembled at another, denominational sets of keys for the actuators respectively coacting with the widely spaced portions thereof, a primary set of accumulator wheels to coöperate with the widely spaced portions of the actuators, a plurality of axially alined sets of wheels to coöperate selectively with the closely assembled portions of said actuators, and printing devices including types set by closely assembled portions of the actuators, and a laterally shiftable carriage which controls selection of the set of wheels.

84. In a machine of the character described, a combination of a denominational series of type-carrying and accumulator-actuating elements having certain actuator portions spaced widely apart and type-carrying portions closely grouped, a set of registering wheels engageable with the widely spaced actuator-portions respectively, a set of keys for each actuator, means for variously measuring the advance of actuators by selective use of keys, means for restoring actuators, means for regulating periods of engagement of wheels and actuators, addi- 120

tional sets of wheels to selectively coöperate with closely grouped portions of the actuators, a paper carriage controlling coöperative relationship of actuators to one or another of said additional sets of wheels, and means for engaging such set with and disengaging it from the actuators.

85. In a machine of the character described, the combination of a denominational series of type-carrying and accumulator actuating elements having certain actuator portions spaced widely apart and type-carrying portions closely grouped, racks on the widely spaced portions of the actuators, gear wheels alining with said racks respectively, numeral wheels united with said gear wheels respectively and accommodated by the spacing apart of the racks, a set of keys for each actuator, means for variously measuring the advance of actuators by selective use of keys, means for restoring actuators, means for regulating periods of engagement of wheels and actuators, additional sets of wheels to selectively coöperate with closely grouped portions of the actuators, a paper carriage controlling coöperative relationship of actuators to one or another of said additional sets of wheels, and means for engaging such set with and disengaging it from the actuators.

86. In a machine of the character described, the combination with a prime mover, denominational key-controlled actuators, and two sets of registering wheels operable thereby; of means driven by the prime mover to engage and disengage the actuators and wheels, and controlling devices applied to said means for changing the period of engagement between either set of wheels and the actuators to reversely rotate wheels of such set without affecting the connection between said means and the other set of wheels, whereby such set may receive the registration of the first set through the setting of actuators by reverse rotation thereof and ensuing engagement of actuators with the second set of wheels.

87. In a machine of the character described, the combination with a prime mover, denominational key-controlled actuators,

and two sets of registering wheels operable thereby, of means driven by the prime mover to engage and disengage the actuators and wheels, and controlling devices applied to said means for changing the period of engagement between either set of wheels and the actuators to reversely rotate wheels of such set without affecting the connection between said means and the other set of wheels, whereby such set may receive the registration of the first set through the setting of actuators by reverse rotation thereof and ensuing engagement of actuators with the second set of wheels together, with provisions for either leaving the first set at zero or restoring its registration.

88. In a machine of the class described, the combination of differentially reciprocatory racks; two sets of accumulating pinions independently engageable with and disengageable from said racks; plural means for engaging and disengaging the racks and pinions, said means severally adjustable to vary the periods of engagement and disengagement between racks and pinions; and means for changing the adjustment of either such means.

89. A machine for listing items in a plurality of columns side by side and printing the total of each column at the foot thereof, comprising printing devices for listing the items in the several columns, a paper carriage for supporting a sheet of paper and moving it transversely of the machine to bring successive vertical columns thereof opposite the printing type, a plurality of sets of accumulator pinions positively controlled in lateral position by said paper carriage, one set for each of the several columns of items to be listed, means for accumulating upon each set of pinions the items of the corresponding column as said items are listed, and means for causing the return of any set of pinions to zero position to set up the type to print the total of the corresponding column of items at the foot thereof.
